UNITED STATES PATENT OFFICE.

MATILDA E. MYERS, OF ATLANTIC CITY, NEW JERSEY.

DESIGN FOR A BADGE OR SIMILAR ARTICLE.

SPECIFICATION forming part of Design No. 32,608, dated May 1, 1900.

Application filed January 31, 1900, Serial No. 3,523. Term of patent 7 years.

To all whom it may concern:

Be it known that I, MATILDA E. MYERS, a citizen of the United States, residing at Atlantic City, in the county of Atlantic, State of New Jersey, have invented and produced a new and original Design for a Badge or Similar Article, of which the following is a specification, reference being had to the accompanying drawings, forming part thereof.

o The leading feature of my design for a badge or similar article is a bar of the form of a shovel or spade and a pendant thereon of the form of a bucket or pail.

Figures 1 and 2 represent side elevations at a right angle to each other of a badge or the like embodying my design.

In the drawings, A designates the badge or similar article, the same consisting of the bar B, presenting the appearance of a shovel or spade, and the pendant C thereon, the latter ²⁰ simulating the appearance of a bucket or pail with sand or shells therein, as at D.

Having thus described my invention, what I claim as new, and desire to secure by Letters Patent, is—

The design for a badge, or similar article, substantially as shown and described.

MATILDA E. MYERS.
